UNITED STATES PATENT OFFICE.

JAMES B. KIRBY, OF CLEVELAND, OHIO.

DESIGN FOR A HANDLE FOR VACUUM-CLEANERS.

44,173.

Specification for Design.

Patented June 10, 1913.

Application filed January 13, 1913. Serial No. 741,613. Term of patent 14 years.

To all whom it may concern:

Be it known that I, JAMES B. KIRBY, a citizen of the United States, residing at Cleveland, county of Cuyahoga, and State of Ohio, have invented a new, original, and ornamental Design for a Handle for Vacuum-Cleaners, of which the following is a specification, reference being had to the accompanying drawing, forming part thereof, in which—

Figure 1 is a front elevation and Fig. 2 is a side elevation, showing my new design of handle.

I claim:

The ornamental design for a handle for vacuum cleaners, as shown.

JAMES B. KIRBY.

Witnesses:

H. T. FISHER,
E. M. FISHER.
